COMBINED COMB, MIRROR AND KEY HOLDER

Clyde H. Hafler, 115 N. 5th St., Allentown, Pa. 18100

Filed Mar. 2, 1973, Ser. No. 337,654

Term of patent 3½ years

Int. Cl. D28—03

U.S. Cl. D86—8

FIG. 1

FIG. 3

FIG. 1 is a rear elevational view of a combined comb, mirror and key holder showing my new design;

FIG. 2 is a front elevational view thereof; and

FIG. 3 is a top plan view thereof.

I claim:

The ornamental design for a combined comb, mirror and key holder, as shown.
